CLAIM

The ornamental design for a dairy barn LED lighting fixture, as shown and described.

DESCRIPTION

FIG. 1 is a front top perspective view of a dairy barn lighting fixture of the present invention;

FIG. 2 is a front view thereof;

FIG. 3 is a back view thereof;

FIG. 4 is a left side view thereof;

FIG. 5 is a right side view thereof;

FIG. 6 is a top view thereof; and

FIG. 7 is a bottom view thereof; and,

FIG. 8 is a bottom perspective view thereof.

In the drawings, the broken lines depict portions of the dairy barn LED lighting fixture that forms no part of the claim.
